UNITED STATES PATENT OFFICE

168,057

VISOR FOR PILOTS' HELMETS

John A. Margwarth, Sherman Oaks, Calif., assignor to Lockheed Aircraft Corporation, Burbank, Calif.

Application June 28, 1952, Serial No. 20,402

Term of patent 14 years

(Cl. D57—1)

To all whom it may concern:

Be it known that I, John A. Margwarth, a citizen of the United States, residing at Sherman Oaks, in the county of Los Angeles, State of California, have invented a new, original, and ornamental Design for a Visor for Pilots' Helmets, of which the following is a specification, reference being had to the accompanying drawings, forming a part hereof.

Figure 1 is a perspective view of a visor for pilots' helmets showing my new design, the visor being shown in raised position;

The dotted lines shown in the drawing are for illustrative purposes only.

I claim:

The ornamental design for a visor for pilots' helmets, substantially as shown and described.

JOHN A. MARGWARTH.
